United States Patent

Des. 235,621
Patented July 1, 1975

235,621

PACKAGING CONTAINER FOR FOOD OR THE LIKE

Richard S. Cawrse, Huron, Ohio, assignor to Cawrse
Dairy, Inc., Lorain, Ohio

Filed May 14, 1973, Ser. No. 360,313

Term of patent 14 years

Int. Cl. D9—03

U.S. Cl. D9—219

FIG. 1

FIG. 2

FIG. 3

FIG. 4

FIG. 1 is a top perspective view of a packaging container for food or the like showing my new design;

FIG. 2 is a side elevational view;

FIG. 3 is a top plan view; and

FIG. 4 is a bottom plan view thereof.

The sides not shown have substantially the same appearance as the side shown.

I claim:

The ornamental design for a packaging container for food or the like, substantially as shown and described.
